UNITED STATES PATENT OFFICE

141,765

DESIGN FOR AN ELECTROLYTIC WATER PURIFIER

Theodore C. Jones, Louisville, Ky.

Application February 27, 1945, Serial No. 118,166

Term of patent 14 years

(Cl. D26—1)

To all whom it may concern:

Be it known that I, Theodore C. Jones, a citizen of the United States, residing at Louisville, in the county of Jefferson and State of Kentucky, have invented a new, original, and ornamental Design for an Electrolytic Water Purifier, of which the following is a specification, reference being had to the accompanying drawing, forming part thereof.

Figure 1 is a front elevation of an electrolytic water purifier, showing my new design,

Figure 2 is a side elevation, and

Figure 3 is a top plan view.

I claim:

The ornamental design for an electrolytic water purifier, as shown.

THEODORE C. JONES.
